ABSTRACT: Apparatus for handling carton blanks or the like as they are being delivered through carton-making equipment, such as from a stripper unit to a delivery unit in in-line paper-converting equipment. The apparatus consists of a diverter mechanism which diverts every other one of the blanks into a circuitous path where it is then deposited on the succeeding blank, thereby doubling up on the blanks, that is arranging them in stacked pairs. Thus, the linear speed of the blanks as they leave the apparatus can be only half as fast as the linear speed of the blanks when they enter the apparatus.

CARTON BLANK HANDLING APPARATUS

BACKGROUND OF THE INVENTION

The invention pertains generally to in-line carton blank apparatus having various units maintained in line for successively performing various functions on the blanks as they pass through the complete line. More particularly, the invention relates to a blank-handling apparatus which double up the blanks and thereby permits the speed of the blanks as they leave the apparatus to be half of that speed of the blanks as they entered the apparatus.

The present invention is located, for example, between a conventional stripper unit such as shown in the patent to Zernov et al., U.S. Pat. No. 3,173,346, issued March 16, 1965 and a delivery unit which may be of the type shown in the Zernov et al. U.S. Pat. No. 3,191,929 issued June 29, 1965 or in the Zernov et al. U.S. Pat. No. 3,160,412 issued Dec. 8, 1964.

One problem in in-line equipment of the type with which the present invention finds particular utility, has been the fact that present-day delivery units are now operating as fast as they can be operated without damaging the product, while the carton blank forming units located farther ahead in the line can be operated much faster than they are presently being operated. However, the units in the forward part of the line, such as the cutter-creaser and stripper units have been held down in speed in order that the subsequent delivery unit is able to handle the blanks.

SUMMARY OF THE INVENTION

The present invention provides carton blank handling apparatus for in-line paper-converting equipment and which apparatus diverts every other blank and compels it to travel in a circuitous path at the end of which it is deposited on the succeeding blank. This apparatus thus "doubles up" or stacks the blanks in pairs, thereby making it possible for them to leave the apparatus at one-half of the speed at which they enter the apparatus.

A more specific aspect of the present invention relates to a novel alternator plate construction that cooperates with a conveying drum in an efficient manner so as to alternately deflect a blank and permit the next blank to pass therethrough. The term "blank" can represent an individual carton or an entire sheet of cartons held together by "nicks". The invention also provides a novel drive means for providing the proper relative speeds between the various parts of the apparatus.

These and other objects and advantages of the present invention will appear hereinafter as this disclosure progresses, reference being made to the accompanying drawings.

BRIEF DESCRIPTION OF THE DRAWINGS

FIG. 1 is a longitudinal cross-sectional view through an apparatus embodying the present invention, certain parts being omitted or broken away for the sake of clarity;

FIG. 2 is a transverse, cross-sectional view taken generally along the line 2-2 in FIG. 1;

FIG. 3 is a view of the alternator means, the view being taken generally along the line 3-3 in FIG. 1;

FIG. 4 is an elevational view of the alternator as shown in FIG. 1;

FIG. 5 is a longitudinal, cross-sectional view taken generally along the line 5-5 in FIG. 1 and showing the cam shaft and its cams;

FIG. 6 is a diagrammatic view of the alternator drive between the various parts;

FIG. 7 is an elevational view of the alternator cam which is shown in FIG. 5;

FIG. 8 is a transverse, cross-sectional view taken along line 8-8 in FIG. 1;

FIG. 9 is a transverse, cross-sectional view taken along line 9-9 in FIG. 1;

FIG. 10 is a transverse, cross-sectional view taken along the line 10-10 in FIG. 1;

DESCRIPTION OF A PREFERRED EMBODIMENT

The apparatus A is designed to fit, for example, between stripper unit SU and a delivery unit DU, both of which are conventional and well known in in-line paper converting equipment. The apparatus A takes the cut and scored blanks B from the stripper unit and delivers them to the delivery unit. Generally, the stripper unit heretofore has been able to operate at a much higher speed than the delivery unit and the present apparatus A acts to slow the speed of the blanks down from its entrance side at the stripper unit to the exit side at the delivery unit.

The apparatus includes two vertically arranged and spaced-apart sides 1 and 2 which are held in rigidly spaced-apart relationship by the crossmembers 3 in the well-known manner. These sides act to rotatably support the various shafts which will be referred to, the shafts being journaled in suitable antifriction bearings, which in turn, are held in the sides in the well-known manner. Therefore, specific reference to the shaft bearings and their support in the sides is not thought to be necessary or desirable as this disclosure progresses. The sides are fabricated from heavy steel plates and the entire unit is free standing.

15 The cut, scored and stripped blanks B are delivered by the rolls 7 of the stripper unit to the entrance of the apparatus and these blanks pass along a first path through the apparatus, which path is generally a straight line. The path is formed by 20 shafts and their support in the sides is not thought to be necessary or desirable as this disclosure progresses. The sides are fabricated from heavy steel plates and the entire unit is free standing.

25 The cut, scored and stripped blanks B are delivered by the rolls 7 of the stripper unit to the entrance of the apparatus and these blanks pass along a first path through the apparatus, which path is generally a straight line. The path is formed by 30 first portion P1, and an exit end in the form of a second portion P2. The first portion P1 of the conveying means includes a roll 10 and a driven roll 11 which are journaled in the sides and over which are trained a series of spaced-apart belts 12. Located adjacent the upper sides of the belts are a pair of spaced-apart rollers 13 and 14, which act to hold the blanks B against belts 12. A guide member 15 is also positioned above the belts for holding the blanks down on the belts 12. Thus, the first portion P1 can convey the blanks in a straight line movement to the second portion P2 of the conveying means.

35 The second portion P2 of the conveying means comprises a pair of rubber covered rolls 17 and 18 disposed one above the other, and also includes a second pair of rubber covered rolls 19 and 20 which are similarly disposed relative to one another. 40 Rolls 18 and 20 can move toward and away from their respective counterpart rolls 17 and 19 so as to open and close the nip between the pairs of rolls. The means for opening and closing the nips, by swinging the lower rolls 18 and 20 toward and away from their counterparts, will be referred to later. The 45 second conveyor portion P2 also includes lower guide plates 21 and 22, and an upper deflector plate 23 positioned above the lower plate 22. The blanks are guided between plates 22 and 23 as they are received from the first conveyor portion P1, through the pair of feed rolls 17 and 18, over the plate 21 and then through the feed rolls 19 and 20 and out the discharge side of the apparatus.

50 Rolls 17 and 18 have constant mesh gears 17a and 18a fixed to their respective ends. Rolls 19 and 20 have constant mesh gears 19b and 20b fixed to their ends.

55 It should be noted that the pairs of rolls are timed to close simultaneously, but the first pair of rolls 17 and 18 are timed so that they open prior to the opening of rolls 19 and 20, as will more fully appear.

60 The entry end of the conveying means, namely portion P1 has a speed twice that of the exit end, i.e. portion P2. More specifically, the peripheral speed of the rolls 17 to 20 is one-half of the linear speed of the belts 12 of the first conveyor portion P1. Thus, as will appear, the blanks leave the apparatus A at one-half the speed of that speed at which they enter the apparatus.

65 Means are provided for deflecting alternate blanks which pass through the apparatus and this means causes the deflected blank to follow around a second path after which it is returned to the first path and deposited on top of the blank

which had succeeded it. Thus, the blanks as they pass through the apparatus are arranged in pairs, that is to say the blanks are doubled up on one another. This permits the blanks to leave the apparatus at one-half the speed of that at which they enter.

The second conveying means includes a driven drum 30 which is located in abutting relationship with the belts 12. Rollers 33, 34 and 35 are journaled on their shafts supported in the sides 1 and 2, and these rollers are located around the drum 30. A series of spaced-apart, endless belts 32 are trained around the rollers 33, 34 and 35 so that the belts 32 wrap around a substantial portion of the periphery of the drum. Fingers 39 of guide member 15 extend between the belts 32 to guide the blanks back onto the belts 12, as will appear.

An alternator 40 is located between the drum and the belts 12 and can swing between a diverting position and a non-diverting position and is arranged so that every other blank is diverted into the second path formed around the drum. That is to say, the alternator diverts every other blank between the drum 30 and the belts 32, thereby carrying the diverted blank completely around the drum and back into the first path where it is deposited on what was its succeeding blank.

The alternator is shown clearly in FIGS. 3 and 4 and includes a generally triangular in cross section shaped cross-member 41 having integral ends 42 and 43. Member 41 has extensions 44 along its length and to which fingers 45 are removably attached by screws 46. The fingers 45 are of sheet metal and are bent at an angle as shown in FIG. 4. It will be noted that the leading edge of the fingers is formed as square teeth 47, for a purpose that will appear. The alternator 40 is pivoted on its stub shafts 48 in sides 1 and 2.

The alternator can be swung between a nondiverting position, that is to an upper position as viewed in FIG. 1, where the teeth 47 of the fingers enter corresponding and complementary grooves 50 which are formed in the periphery of the drum 30. This tooth construction for the ends of the fingers has proved to be highly desirable because the ridges 51 between the grooves 50 in the drum 30 can act to fully support the blanks, more particularly, they act to fully support any irregular edge of the blanks. With this construction, the fingers can be completely moved out of the straight path of the blanks.

When the alternator is swung to the lower position, the forward edge of the fingers drop below and between the belts 12, thereby causing the oncoming blank to be delivered up into the secondary path around the drum.

Means are provided for swinging or oscillating the alternator 40 between the upper nondiverting position and the lower diverting position as follows.

An alternator cam 60 (FIGS. 5 and 7) is fixed to shaft 61 and a cam follower 62 rides around the periphery of cam 60 and transmits its resulting motion through an arm 63 which is fixed on a shaft 64 that is journaled in sides 1 and 2. Adjacent each of shaft 64 is fixed an arm 66 and a pair of adjustable links 65 connects the arms 66 to the ends of the alternator 40. Thus, as the cam shaft is rotatably driven by means to be described, the alternator is swung up and down in timed relationship with other components of the apparatus, as will appear.

The alternator is biased to the downward, diverting position by a pair of spring loaded struts 67 acting between blocks 68 on the frame and the upper side of the alternator 40. One of these spring loaded struts 67 is located at each end of the alternator plate.

Cam means are also provided for operating the two rollers 18 and 20 at the exit end of the conveying means. This means includes cams 70 and 71 which are also fixed to shaft 61, and through their respective cam followers 72 and 73 mounted on arms 74 and 75 which in turn are fixed to shafts 76 and 77, pairs of arms 78 and 79 which are fixed to the ends of shafts 76 and 77, and respective adjustable links 80 and 81, which all act to swing the respective rolls 20 and 18 about their pivot points 82 and 83. Thus, the rotation of the cams causes opening and closing of the nips of the pair of rolls 17, 18 and 19, 20.

Rollers 18 and 20 are biased to the downward position by pairs of leaf springs 117 and 118 acting between arms 78 and 79 and frame supported studs 119 and 120.

The various rollers are drivingly connected together in timed relationship with one another as follows.

The power for the apparatus comes from the toothed timing sprocket 100 fixed with the stripper drum 101 of the stripper unit SU. Power is furnished through the timing belt 102 to the large timing sprocket 103 that is fixed to the cam shaft 61. This belt is also trained over a pulley 104, and is properly tensioned by the spring loading tensioning strut 105.

A V-belt pulley 106 is also fixed to the cam shaft 61 and a V-belt 107 is trained around pulleys 108 and 109 which are fixed to the shafts 20a and 18b respectively, of the out-feed rolls 20 and 18. The sprocket 100 is one-half the size of the sprocket 103 and thereby the speed of the sprocket 103 is one-half that of the sprocket 100. The arrangement is such that the peripheral speed of the rolls 20 and 18 is one-half the speed of drum 101. As the pulley 104 is fastened to the shaft 11a of roller 11, the linear speed of the belts 12 is twice that of the peripheral speed of the rolls 20 and 18. Thus, the speed of the blanks as they leave the apparatus is one-half the speed at which they are conveyed by the first conveying portion P1.

Drum 30 is driven by the pulley 111 fixed to shaft 30a of the drum. Sprocket 111 receives its power through the V-belt 112 and sprocket 113 fixed to the shaft 14a of roller 14. The shaft of roller 14 receives its power from the gear 115 fixed to the shaft 11a of roller 11 and gear 116 fixed to the shaft 14a of roller 14. Gears 115 and 116 are in constant mesh and are of a one-to-one ratio. Thus the peripheral speed of drum 30 is the same as the linear speed of belts 12.

We claim:

1. Carton blank handling apparatus having an entrance side and an exit side for blanks passing therethrough, conveying means defining a path through said apparatus and for guiding blanks between said entrance side and said exit side, said conveying means having an entrance portion and an exit portion, said exit portion being driven at a linear speed which is approximately one-half of the speed of said entrance portion, said exit portion having relatively shiftable nip rollers, second conveying means for conveying a selected blank in a second path away from and back into said first path, and an alternator means for alternately deflecting every other blank from said first path and guiding it into said second path whereby said deflected blanks are diverted through said second path and then reenter said first path where they are deposited on their respective succeeding blanks, and means including cam means having connecting means with said nip rollers for opening and closing thereof in timed relationship with said second conveying means.

2. The apparatus as set forth in claim 1 further characterized in that said second conveying means includes a rotatable drum located adjacent said first portion of said conveying means, and an endless belt in engagement with the periphery of said drum for conveying blanks between said belt and said drum in a circuitous path.

3. The apparatus as set forth in claim 2 further characterized in that said alternator means includes an oscillatable plate which has a leading edge that is swingable (1) against said drum to permit the blanks to pass through said apparatus along said first path, and (2) to a position away from said drum to divert said blanks into engagement with said drum and belt.

4. The apparatus as set forth in claim 3 further characterized in that said cam means includes cam means for actuating said alternator means.

5. Carton blank handling apparatus comprising conveying means having an entry end and an exit end and defining a path through said apparatus and for guiding blanks therethrough, said exit end having relatively shiftable nip rollers, second conveying means for conveying a selected blank in a second path away from and back into said first path, and an alternator means for alternately deflecting every other blank from said first path and guiding it into said second path whereby said

deflected blanks are diverted through said second and then reenter said first path where they are deposited on their respective succeeding blanks, and drive means including cam means having connecting means with said nip rollers for opening and closing thereof in timed relationship with said second conveying means.

6. The apparatus as set forth in claim 5 further characterized in that said second conveying means includes a rotatable drum located adjacent said entry end of said conveying means, and an endless belt in engagement with the periphery of said drum for conveying blanks between said belt and said drum in a circuitous path.

7. The apparatus as set forth in claim 6 further characterized in that said alternator means includes an oscillatable plate which has a leading edge that is swingable toward said drum so as to permit the blanks to pass through said apparatus along said first path, and a position away from said drum whereby said blanks are diverted by said alternator means into engagement with said drum and belt.

8. The apparatus as set forth in claim 7 further characterized in that said drive means includes cam means connecting said drive means with said alternator means.
